UNITED STATES PATENT OFFICE.

HARRY E. CAMPBELL, OF NEW YORK, N. Y.

WINDOW FRAME AND SASHES.

1,273,454.

Specification of Letters Patent. Patented July 23, 1918.

Application filed April 1, 1918. Serial No. 225,916.

To all whom it may concern:

Be it known that I, HARRY E. CAMPBELL, a citizen of the United States, residing at New York, in the county of New York and State of New York, have invented a certain new and useful Improvement in Window Frames and Sashes, of which the following is a specification.

The invention is a window-frame and sash, wherein all the structural parts are of wood, except the laterally extending metal sash plates and metal angle-bars therefor. The invention consists in the construction more particularly hereinafter described.

15 In the accompanying drawings—

Figure 1 is an elevation showing a portion of the two sashes and of the jamb adjacent thereto, the jamb wall being broken away at its upper portion to show the underlying parts in vertical section. Fig. 2 is a section on the line 2, 2 of Fig. 1.

Similar letters of reference indicate like parts.

A and B are sliding sashes, provided with 25 any suitable counterbalancing means, not shown. The sash frames are of wood, and the glass panes C are seated in said frames and secured by strips D in any suitable way. The two jambs respectively on opposite sides

30 of the sashes are alike, so that a description of one jamb applies to both. Said jambs are hollow, and their walls are of wood. One of said jambs is shown at E, and comprises the following parts: a rear wall F, 35 an outer side wall G, a front wall H, and an inner side wall formed as hereinafter described. The outer side wall G is secured to the rear wall F and to the front wall H. Seated at one edge in a mortise in rear wall

40 F is a wooden bar I which projects into the space within the jamb and is parallel to wall G. Secured to the face of bar I is a partition J, with the face of which the sashes A, B are in sliding contact, said bar covering 45 the joint between said sashes. The outer member K of the inner jamb wall is secured to front jamb wall H, and the inner member L is secured to rear wall F and preferably meets bar I.

50 Between the member K and partition J and between partition J and member L are gaps or vertical slots, which extend from top to bottom of the jamb. In the gap between member K and partition J are two 55 angle-strips M, N of metal, the apexes of the angles facing one another—a space being

left between said apexes. These angle-strips are respectively secured to their supports—namely, member K and partition J—in any suitable way. Preferably, as shown, I insert 60 one arm of the strip in a mortise in its support and attach the other arm to a suitably beveled portion of said support. In the gap between partition J and member L are two 65 similar strips O, P, respectively secured to said partition J and member L in the manner already described.

On the sashes A, B are laterally extending metal plates Q, R, which preferably enter mortises in the edges of said sashes, and 70 may be secured therein by screws S. The plate Q on sash B enters between the angle-strips M, N, and the plate R on sash A enters between the angle-strips O, P. Both plates, therefore, enter the jamb and preferably 75 terminate at their free vertical edges in sliding contact with the bar I. I preferably secure upon the face of bar I, means for protecting said face against the wear thereon due to the sliding of said plates, such as 80 a metal plate T, against which the free edges of said plates bear.

It will be obvious from the foregoing that all the structural members are of wood, excepting the lateral plates Q, R, the angle strips M, N and O, P, and, when present, the wearing-plate T; also, that market wooden sashes can here be used, since the lateral metal plates Q, R are easily attached to them. Metal angle-strips are also obtainable, and can be applied by any house carpenter.

I claim:

1. A window-frame and sash construction, comprising a hollow jamb of wood having in its inner wall a vertical slot, metal angle-strips secured on opposite sides of said slot, with the apexes of their angles approximated, a sash of wood, and on said sash a laterally extending metal plate entering said 95 jamb through said slot between and in contact with said angle-strips.

2. A window-frame and sash, as in claim 1, the said laterally extending plates being received in mortises in the side rails of said 100 sash.

3. A window-frame and sash, as in claim 1, each of said angle-strips having one arm entering and secured in the jamb wall adjacent to said slot, and the other arm bearing 110 upon a support.

4. A window-frame and sash, comprising

a hollow jamb of wood having in its inner wall two parallel vertical slots, a bar of wood, fixed within said jamb and facing said slots, metal angle-strips secured on opposite sides of said slots, with the apexes of their angles approximated, two sliding sashes of wood, and on each sash a laterally extending metal plate, the said plates respectively entering said jamb through said slots and between

and in contact with said angle-strips and 10 having their free edges in sliding contact with said bar.

In testimony whereof I have affixed my signature in presence of two witnesses.

HARRY E. CAMPBELL.
